[57] CLAIM

The ornamental design for a basketball practice target,
as shown and described.

DESCRIPTION

FIG. 1 is a top plan view of a basketball practice target
showing my new design;

FIG. 2 is a front perspective view thereof; and,
FIG. 3 is a right side elevational view thereof, the side
opposite being substantially a mirror image.

The broken lines showing a basketball net and rim in
FIGS. 2 and 3 represent environment only.

FIG. 1

FIG. 2

FIG. 3
